UNITED STATES PATENT OFFICE.

PATRICK H. MAGIRL, OF BLOOMINGTON, ILLINOIS.

FURNACE.

1,163,676.

Specification of Letters Patent. Patented Dec. 14, 1915.

Application filed May 5, 1915. Serial No. 26,027.

To all whom it may concern:

Be it known that I, PATRICK H. MAGIRL, a citizen of the United States, residing at Bloomington, in the county of McLean and State of Illinois, have invented certain new and useful Improvements in Furnaces, of which the following is a specification.

This invention relates to furnaces for warming air and the principal features of novelty are the use of a double or divided rear breeching and in the arrangement of the direct draft in connection with the rear breeching.

A furnace embodying the invention is illustrated in the accompanying drawings, in which:

Figure 1 is a vertical longitudinal section of the furnace, the casing being omitted; Fig. 2 is a vertical transverse section looking toward the rear and showing the rear breeching, the flue plates and the direct draft connection; Fig. 3 is an enlarged section through the direct draft flue on the line 3-3 of Fig. 2; Fig. 4 is an enlarged section through a direct draft flue the section being taken on the line 4-4 of Fig. 3; Fig. 5 is an enlarged axial section of one of the main flues showing the connecting joints with the front and rear flue plates; and Fig. 6 is a fragmentary view looking at the left end of the flue shown in Fig. 5.

The furnace shown in the drawings is usually inclosed in a brick or other casing which confines the air to be heated and causes it to flow in contact with the fire box and flues. This casing being common in the art is not illustrated. The furnace has the usual front 11 of cast iron provided with the usual fuel door 12 and ash pit door 13 as well as suitable cleanout openings (not shown). To the front 11 are bolted the castings forming the fire box 14 and ash pit 15, the surfaces of the fire box walls being corrugated to increase their surface.

Leading from the rear of the fire-box 14 are two fire box extensions 16 also provided with corrugated surfaces and these extensions terminate in the breechings 17 which are spaced apart. These breechings are semi-circular in side elevation and project upward beyond the fire-box extensions 16 and carry on their forward sides the flue plates 18. These are provided with flue openings 19, which are provided with spaced annular flanges 20 and 21 for receiving the bell

shaped ends 22 of the flues 23. The flues 23 are held in sealing relation with the plates 18 by means of collars 24 and bolts 25 as most clearly shown in Fig. 5. Asbestos or other packing 26 is used at the point indicated to secure a gas tight joint.

The flues 23 extend forward from the breechings 17 over the fire box 14 and its extensions 16 and enter a smoke box or manifold 27 bolted to the furnace front 11 as clearly shown in Fig. 1. The forward ends of the flues 23 are provided with spaced annular flanges 28 and 29, the end flanges 28 being small enough to pass through the flue openings 30 in the smoke box 27. The other flanges 29 bear against the wall of the smoke box around the opening 30 and produce a sealed joint. Flanges 31 surrounding the flue openings 30 hold the flues 23 centered and aid in retaining packing 32. Externally threaded divided sleeves 33 are placed around the ends of the flues 23 behind the flanges 28 and nut rings 34 threaded therein hold the parts of the sleeves in assembled relation and force them against flanges 28 to produce the necessary joint sealing pressure.

There are three of the flues 23 leading from each breeching in the furnace illustrated, but the number is not material and will vary according to the size and purpose of particular furnaces.

A horizontal smoke pipe 35 leads from the smoke box 27 to the uptake 36 at the rear of the furnace. Alined with the uptake 36 is a direct draft passage 37 and this is connected by a Y connection 38 to the two breechings 17. The Y connection 38 is placed between the breechings 17 and is connected to them and to the direct draft passage 37 by a special form of joint illustrated in Fig. 4. The abutting ends of the flues all have inter-engaging flanges 39 and these are clamped in engagement by divided encircling rings 40 U-shaped in cross section the two parts of which are hinged together at 41. A bolt 42 is provided to hold the rings clamped around the flues.

The direct draft is controlled by a sliding damper 43 which is actuated by a rod 44 leading through pipe 35 to the front of the furnace.

The construction described permits ready replacement of parts, secures gas tight joints at all points and simplifies the construction of furnaces of this type. The location of

the direct draft at the rear is an important improvement, the direct draft in this type of furnace having heretofore been located in the top of the fire box at the front. The 5 improved construction avoids the short circuiting of the entire heating surface by the direct draft which necessarily occurs in prior structures, and yet secures a wholly satisfactory direct draft.

10 Having thus described the invention, what I claim is:—

1. In a furnace, the combination of a fire box; a pair of breechings spaced apart and communicating with the rear of the fire box; 15 an uptake adjacent said breechings; a heat radiating flue structure communicating with said breechings and uptake; a direct draft connection mounted between said breechings and communicating therewith and with said uptake; and a damper for opening and closing said direct draft connection.

2. The combination with a furnace including a fire-box, a pair of spaced breechings communicating therewith and an uptake 25 connection, of a direct draft connection comprising a Y coupling mounted between said breechings and communicating therewith and with said uptake connection.

3. In a furnace, the combination of a fire 30 box; a pair of breechings spaced apart and communicating with said fire-box; an up-

take adjacent said breechings; a heat radiating flue structure communicating with said breechings and uptake; a flanged Y connection mounted between said breechings 35 and communicating therewith and with said uptake; and clamping rings U-shaped in cross section engaging the flanges of said Y connection for holding the same in close connection with said breechings and uptake. 40

4. In a furnace the combination of a fire box; two horizontal fire box extensions projecting rearwardly therefrom; a pair of breechings one applied to the rear of each of said fire box extensions, the extensions 45 and breechings being respectively spaced apart to permit the passage of air between the same; heat radiating flue structures, one extending forward from each of said breechings above said extensions and fire box; a 50 forward smoke box connecting with said flue structures; an up-take at the rear of the furnace; a smoke pipe mounted between said flue structures and connecting the smoke box to said up-take; a Y-connection mounted 55 between said breechings and offering a communication direct from the same to said up-take; and a damper controlling the last named connection.

In testimony whereof I have signed my 60 name to this specification.

PATRICK H. MAGIRL.
